UNITED STATES PATENT OFFICE.

EDWARD G. GROSS, OF COLUMBUS, GEORGIA.

SEWER-TRAP CAP.

1,245,903.

Specification of Letters Patent. Patented Nov. 6, 1917.

Application filed July 11, 1916. Serial No. 108,635.

To all whom it may concern:

Be it known that I, EDWARD G. GROSS, a citizen of the United States, residing at Columbus, in the county of Muscogee and 5 State of Georgia, have invented new and useful Improvements in Sewer-Trap Caps, of which the following is a specification.

This invention relates to improvements in sewer well caps, and the primary object of 10 the same is to so construct the cap to permit of the free access of water therein from the gutters and preventing the escaping of noxious vapors rising from the water collected within the sewer well or trap.

15 A further object of the invention is the provision of a trough having detachable connection with the sewer cap, and serving as a means for permitting of the inlet of the water within the sewer well, and preventing overflowing of the sewer wells or 20 traps which frequently occurs in cases of unusually heavy rain.

A still further object of the invention is the provision of a gravity closing door for 25 the inlet of the trough for preventing the escapement through the grating of the trough of noxious vapors or gases rising from the water collected within the sewer well.

30 With the above and other objects in view, the invention consists in the novel features, details of construction and combination of parts which will hereinafter be more fully set forth, illustrated in the accompanying 35 drawing and pointed out in the appended claims.

Figure 1 is a perspective view of a sewer cap;

Fig. 2 is an end elevation;

40 Fig. 3 is a detail section clearly illustrating the manner of connection of the trough with the sewer cap.

Referring more specifically to the accompanying drawing in which like characters 45 of reference refer to corresponding parts in the several views, 5 designates an angular sewer cap which may be constructed of any suitable material such as cast iron, brick or cement and embodies a flat top 6 and a depending front 7. The top 6 is provided with the usual clean-out opening 8 and it is to be understood that this sewer trap cap is to be placed over the well-known sewer wells and flush with the level of the sidewalk, while the front wall 7 is embedded

within and at a point below the street level, the purpose of which will be hereinafter fully set forth.

The front wall 7 of the sewer trap is formed with an upper longitudinally disposed opening 9, and a lower longitudinally disposed opening 10, the said openings 9 and 10 being disposed in superposed relation one to the other, and arranged for the greater portion of the length of the front wall 7. 60 In order to prevent the entrance of leaves, twigs, trash or the like, within the opening 9 of the cap, I provide a guard 11, including a series of spaced rods 12. Formed integral with the front wall 7 and interiorly thereof, 65 at points to opposite sides of each of the openings 9 and 10, are U-shaped hangers 13 and 14, in which are journaled the trunnions 15 and 16 of gravity closing valves 17 and 18 respectively, thence the valves are 70 swingingly supported by the hangers, and the valve 17 through the medium of its weight 19, automatically closes the top opening 9, while the door 18 through the medium of its weight 20, automatically closes the 75 lowermost opening 10, thereby preventing noxious vapors, gases or vermin rising from the water collected within the sewer wall from escaping from such well. It is to be further understood that the water from 80 the streets and gutters entering the respective openings 9 and 10 will force the doors 17 and 18 to an open position, and be deposited within the sewer well, not shown. The doors 17 and 18 when in closed position, 85 abut or engage with the tapering rib 19', for assuring of the doors assuming a 90 full closed position at all times.

It frequently happens during or after a hard rain that the sewer well overflows for 95 the reason that the inlet of such well is not sufficient to permit of the drainage of the water from the streets or gutters, and to this end, I attempt to overcome this objectionable feature by providing the trap 100 with a trough 21. This trough may be constructed of metal, masonry, or the like material, and is preferably embedded within the gutter below the street level and is of substantially rectangular configuration embodying end walls 22, a front wall 23 and a downwardly and rearwardly inclined bottom wall 24. The trough is closed through the medium of a grating 25. Formed on the front wall 7 of the sewer cap at a point 105

slightly below the top opening 9 and at points adjacent the ends of the cap is a pair of dove-tailed projections 26, while arranged below said projections 26 is a pair of 5 sockets 27, the projections 26 being adapted to be engaged by the sockets 28 formed in the rear wall 29 of the trough 21, while the sockets 27 receive the depending projection 30 formed on the bottom wall 24 of the 10 trough 21, and as will be seen through the engagement of the trough with the projections 26 and extension 30, the trough is detachably mounted upon the front wall 7 of the trap and over the lowermost opening 15 10.

In briefly describing the operation of this invention it is to be stated that the cap is positioned over the well of the sewer trap, the latter not being shown, while the trough 20 is properly embedded within the gutters and below the street plane and during the action of draining of the streets and pavements, the water will pass between the rods 12 as well as through the grating 25 of the 25 trough. The water passing through the bars 12 will force the door 17 to an open position and pass within the sewer well, while the water deposited within the trough 21, through the medium of the inclined bottom 30 wall 24 will be directed through the lowermost opening 10 and in turn swing the door to an open position and thence be deposited within the sewer well as is clearly understood. After the streets have been fully 35 drained and the water has stopped passing within the respective openings 9 and 10 of the cap, the doors then close by gravity through the action of their weights and conceal the openings to the extent of preventing the noxious vapors, gases and vermin rising from the water collected within the sewer well from escaping from the sewer, and further serve to prevent the breeding of vermin or mosquitos from rising 40 from the water deposited in the well. 45

From the foregoing description, taken in connection with the accompanying drawing, the advantages of construction and of the method of operation will be readily apparent to those skilled in the art to which the 50

invention relates, and while I have described the principles of operation of the invention, together with the device which I now consider to be the best embodiment thereof, I desire to have it understood that 55 the device shown is merely illustrative, and that such changes may be made when desired as are within the scope of the claims appended thereto.

I claim:

1. A device of the character set forth, a sewer trap having a front wall provided with a pair of superposed openings, a gravity closing valve for each of said openings, a tapering rib arranged on the inner 65 face of the front wall and to opposite sides of said opening, a trough detachably connected on the exterior face of the front wall of the sewer cap and over the openings formed therein, and a grating covering said 70 trough.

2. A device of the character set forth, a sewer cap comprising a front wall formed with upper and lower openings, a gravity closing valve for each opening, projections 75 on the exterior face of the front wall, and a trough having sockets for receiving the projections of the sewer cap to support the trough horizontally of the front wall and in communication with the lower opening 80 thereof, and a grating covering said trough.

3. A device of the character set forth comprising an angular sewer trap, the vertical portion of which being formed with a pair of openings, a pair of sockets formed 85 on the exterior face of the vertical portion of the sewer cap, a gravity closing door for each of the openings, a trough having a depending projection, the projection of the trough engaging in the sockets of the cap 90 for supporting the former on the vertical portion of the latter, and a grating for said trough.

In testimony whereof I affix my signature in presence of two witnesses.

EDWARD G. GROSS.
